CONVEYOR CARRIER

Joseph John Soncrant, Denville, N.J., assignor to Thomas Electronics, Inc., Passaic, N.J., a corporation of New Jersey

Application January 30, 1958, Serial No. 712,219

11 Claims. (Cl. 294—92)

This invention relates to a conveyor and more particularly relates to a carrier for transporting television cathode ray tubes.

In the current day manufacture of television cathode ray tubes, it is conventional practice to transport the tubes along a conveyor line so that the various manufacturing operations can be performed upon the tubes at sequentially spaced operating positions. The tubes are normally carried with the neck down and in most instances the carriers utilized are specially designed to carry a particular size and shape bulb. In other cases, adjustable carriers have been provided wherein the same carrier may be utilized for carrying different size and shaped bulbs after certain adjustments in the carrier are effected. Metal carriers have generally been used and in some instances difficulty has been encountered with breakage of the bulbs and dangerous conditions have been created where these metal carriers have come into contact with some of the high voltage leads which are necessarily applied to the cathode ray tube structure during the manufacturing process.

It is a primary object of the present invention to provide an improved cathode ray tube carrier of a unitary rigid construction which is capable of handling all sizes and shapes of cathode ray tubes.

It is another object of the invention to provide an improved cathode ray tube carrier capable of supporting all sizes and shapes of cathode ray tubes in substantially the same position without the necessity for any adjustments in the carrier itself.

It is a still further object of the invention to provide an improved cathode ray tube carrier of the foregoing type construction in such a manner as to eliminate damage to the tube through contact with the carrier and to minimize the danger of shock through inadvertent energization of the carrier with a high potential.

It is a still additional object of the invention to provide a carrier of the foregoing type which can be manufactured at a low cost from readily available stock material.

These and further objects and advantages of the invention will become more apparent upon reference to the following specification and claims and appended drawings wherein:

Figure 1 is a side elevation of a television cathode ray tube carrier showing the dimensions of a carrier constructed to handle current standard bulb types;

Figure 2 is a side elevation of a television cathode ray tube carrier constructed according to the invention showing three different sized and shaped bulbs located in the carrier;

Figure 3 is a plan view of the television cathode ray tube carrier of Figures 1 and 2; and

Figure 4 is an additional side elevation of the television cathode ray tube carrier showing still further different size and shaped television cathode ray tubes mounted therein.

Referring more particularly to the figures of the

2

drawing, there is seen a television cathode ray tube carrier consisting of a generally C-shaped member 10 preferably formed from pipe and having parallel depending legs 12 and 14 terminating in inwardly extending portions 16 and 18. The parallel depending legs 12 and 14 are attached to inwardly extending portions 20 and 22 of the C-shaped member which are at angles of 135° to the depending legs. The inwardly extending portions 20 and 22 are connected to a horizontal top member 24 having an attaching member 26 secured thereto and extending upwardly therefrom. A mounting hole 28 may be provided in this attaching member for securing the carrier to the conveyor proper.

Attached to the ends of the inwardly extending portions 16 and 18 of the C-shaped member 10 are a first pair of V-shaped members shown generally at 30 and 32 in Figure 3. Each V-shaped member consists of a single piece of rod stock bent so as to form an apex portion 34 with the legs 36 extending at an angle thereto. The apex portions 34 are welded to the ends of the inwardly extending portions 16 and 18 of the C-shaped member 10.

Depending from the junction of the apexes of the first pair of V-shaped members and the ends of the inwardly extending portions 16 and 18 of the C-shaped member are a pair of support arms 38 and 40 which terminate below the first pair of V-shaped members approximately in vertical planes passing through the ends of the legs of these V-shaped members. A second pair of V-shaped members shown generally at 42 and 44 in Figure 3 are attached to the depending support arms 38 and 40 and extend inwardly toward one another. Each of these V-shaped members is formed similarly to the first pair of V-shaped members and consists of an apex portion 46 bent to provide arms 48 extending at an angle thereto.

The second pair of V-shaped members lie in a common plane below the plane which contains the first pair of V-shaped members and the spacing between the apexes 40 of the second pair of V-shaped members is approximately one-half of the spacing between the apexes of the first pair of V-shaped members, as is shown with further precision by the dimensions indicated in Figure 1 of the drawing. The legs of these V-shaped members in the first pair form an angle with respect to one another of 94°, while the legs of the V-shaped members in the second pair form an angle with respect to one another of 86°.

The entire carrier is coated with a resilient coating 50 such as polyvinyl chloride which may be applied to a thickness of one-eighth inch. This coating serves as a cushion between the metal carrier and the glass bulbs and also provides insulation against the high voltages which are applied to the tubes during the manufacturing process. The coating may be applied by dipping the carrier into a cold thick suspension of the resin in plasticiser and then curing at an elevated temperature during which time the coating becomes tough and homogeneous, as is well known to those skilled in the art. Since the C-shaped portion of the carrier is formed of hollow pipe a pressure arises inside the pipe during the curing operation and small weld defects may cause bubbles to escape which would disrupt the resilient coating. In order to prevent this, a small vent hole is 65 provided at 50 at the top of the C-shaped member in order to allow for air expansion.

Referring to Figures 2, 3 and 4, the outlines of standard television cathode ray tube bulbs are shown in broken lines with the size and shape of the bulb indicated on 70 the drawings. It will be seen that a large variety of bulbs can be accommodated by the carrier and that some of these bulbs, such as a 10-inch 90° bulb, can be sup-

ported in either of two positions as is indicated in Figure 3.

Some of the bulbs are carried only by the upper arms, some by only the lower arms, while other bulbs are supported by both sets of arms. The open construction of the carrier permits easy insertion and removal of the bulbs, while at the same time securely holding the bulbs in position to prevent accidental dropping. It is apparent that the large variety of bulb sizes and shapes are accommodated without adjustment of the carrier and that bulb breakage and dangerous high potential energization of the carrier are prevented by means of the resilient coating. The unit is extremely simple in construction and low in cost and is not readily susceptible to serious damage.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description and all changes which come within the meaning and range of equivalency of the claims are therefore intended to be embraced therein.

What is claimed and desired to be secured by United States Letters Patent is:

1. A carrier for conveying cathode ray tubes comprising a generally C-shaped suspension member having spaced depending legs which terminate in inwardly extending portions, a first pair of generally V-shaped support members having their apexes attached to said inwardly extending portions and having the legs thereof extending toward one another, a pair of depending members extending downwardly from said inwardly extending portions, a second pair of generally V-shaped support members having their apexes attached to said depending members and having the legs thereof extending toward one another, the apexes of said second pair of V-shaped members being spaced less than the apexes of said first pair of V-shaped members.

2. A carrier as set out in claim 1 wherein said carrier is coated with a resilient insulating material.

3. A carrier for conveying cathode ray tubes comprising a generally C-shaped suspension member having

spaced depending legs which terminate in inwardly extending portions, a first pair of generally V-shaped support members having their apexes attached to said inwardly extending portions and having the legs thereof extending toward one another, a pair of depending members extending downwardly from said inwardly extending portions toward one another, and a second pair of generally V-shaped support members having their apexes attached to said depending members below the level of said inwardly extending portions and having the legs thereof extending toward one another, the apexes of said second pair of V-shaped members being spaced less than the apexes of said first pair of V-shaped members.

15 4. A carrier as set out in claim 3 wherein each of said V-shaped members includes an angle of approximately 90° between its legs.

5 5. A carrier as set out in claim 4 wherein the angles included between the legs of the first pair of V-shaped 20 members is slightly greater than 90° and the angle included between the legs of the second pair of V-shaped members is slightly less than 90°.

6 6. A carrier as set out in claim 3 wherein the connection points between said second pair of V-shaped 25 members and said depending members lie approximately in vertical planes containing the inner ends of the legs of the first pair of V-shaped members.

7 7. A carrier as set out in claim 3 wherein said carrier is coated with a resilient insulating material.

8 8. A carrier as set out in claim 3 wherein said carrier is formed of hollow pipe and has a hole in said C-shaped member to serve as a vent.

9 9. A carrier as set out in claim 6 wherein the distance between the apexes of said first pair of V-shaped 35 members is approximately twice the distance between the apexes of said second pair of V-shaped members.

10 10. A carrier as set out in claim 9 wherein the depending legs of said C-shaped member are substantially parallel over a portion thereof.

40 11. A carrier as set out in claim 10 wherein said carrier is coated with a resilient insulating material.
